[57] CLAIM

The ornamental design for a swabbing stick, substantially as shown.

DESCRIPTION

FIG. 1 is a top plan view of a swabbing stick showing my new design;

FIG. 2 is a front elevational view thereof;

FIG. 3 is a side plan view thereof; and

FIG. 4 is a bottom plan view thereof.

Characteristic feature of my design resides in the elliptical cross-sections of the swab and stick.

FIG. 1

FIG. 2

FIG. 3

FIG. 4
